CLAIM

The ornamental design for a laptop as shown and described.

DESCRIPTION

FIG. 1 is a front elevational of the laptop showing the design, wherein the laptop is in folded position;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a perspective view thereof;

FIG. 8 is a perspective view thereof where the laptop is in a first opened position;

FIG. 9 is a front elevational of the laptop showing the design, wherein the laptop is in a second opened position;

FIG. 10 is a rear elevational view thereof;

FIG. 11 is a left side view thereof;

FIG. 12 is a right side view thereof;

FIG. 13 is a top plan view thereof;

FIG. 14 is a bottom plan view thereof; and,

FIG. 15 is a perspective view thereof.
